United States Patent Office

Des. 199,789
Patented Dec. 15, 1964

199,789

SOFA

Adrian M. Pearsall, Forty Fort, Pa.
(1212 Scott St., Wilkes-Barre, Pa.)

Filed Apr. 14, 1964, Ser. No. 79,482

Term of patent 14 years

(Cl. D15—11)

I claim:

The ornamental design for a sofa, substantially as shown.
